UNITED STATES PATENT OFFICE.

WAINWRIGHT B. GERVAIS, OF CHICAGO, ILLINOIS, ASSIGNOR TO VARIETY FIRE DOOR COMPANY, OF CHICAGO, ILLINOIS, A CORPORATION OF ILLINOIS.

SHEET-METAL DOOR.

Application filed November 2, 1925. Serial No. 66,138.

This invention relates to sheet metal doors and its objects are the provision of a generally improved and simplified sheet metal door construction that may be economically produced.

The construction is characterized by facility of erection. It may be easily and quickly assembled without the use of rivets, bolts, or the like. The stile and general frame construction are standardized and the construction of the rails, panels and other parts are also standardized and interchangeable, so that the doors may be conveniently erected with different panel and rail arrangements.

More particularly, the invention provides an improved stile structure, an improved panel and rail structure and an improved mode of attaching the panels and rails to the frame or stiles.

Further features are the manner of forming and attaching the panel molding and the manner of providing the door with hangers, guide means and filler means, where desired. The hanger means may be adjustable to expedite proper hanging of the door in spite of settling and such structural variations as may occur.

My improved sheet metal construction has a wide range of utility. I contemplate its employment for the construction of elevator doors and the like. A door construction embodying my invention has all the advantages of lightness and strength and, in addition, is fire and substantially sound proof.

The invention is illustrated in the accompanying drawings, in which:

Fig. 1 is a front elevational view of a door embodying the invention;

Fig. 2 is a vertical section taken on the line 2—2 of Fig. 1;

Figure 2^A is a fragmentary top plan view showing the adjustable hanger provision;

Fig. 3 is a horizontal section taken through one of the rails on the line 3—3 of Fig. 1;

Fig. 4 is a horizontal section through one of the panels on the line 4—4 of Fig. 1;

Fig. 5 is a fragmentary elevation of one corner of the door showing the manner of attaching the panel molding;

Fig. 6 is a detail isometric view of one of the molding attaching clips;

Fig. 7 is a fragmentary detail isometric view of one of the upper rail members.

Fig. 8 is a fragmentary detail isometric view of the other upper rail member; 55

Fig. 9 is a fragmentary detail isometric view of one of the intermediate rail members;

Fig. 10 is a similar view of the other intermediate rail member; 60

Fig. 11 is a front elevational view of a modification;

Figs. 12 and 13 are fragmentary vertical sections showing alternative forms of panels; 65

Fig. 14 is a detail section showing one manner of attaching an operating member to the door.

Referring first to Figs. 1 to 10, the door comprises stiles 5, 5, a top rail 6, an intermediate rail 7, a bottom rail 8 and panels 9 and 10.

The stiles 5 may be formed of sheet metal suitably shaped into generally rectangular hollow configuration in transverse section as 75 shown in Figs. 3 and 4. Along one side of the door each stile 5 has along its inner edge a tongue 12 turned back and lying in the direction of the thickness of the door. Along the opposite side of the door each stile 5 has 80 a tongue 14 turned back and lying in the direction of the width of the door. The inner corners of each stile 5 between the tongues 12 and 14, are open at 15, and closing and re-enforcing these corners are vertical strips 85 16 having tongues 18 held between the tongues 14 and the adjacent side of the stile 5, and tongues 20 turned back and inter-engaging with the tongues 12. The tongue formation along the inner edges of the stile 5 leaves said 90 inner edges open and the strips 16 close and lock said inner edges together and re-enforce and strengthen the same throughout substantially the entire vertical dimension or 95 height of the door.

The upper rail 6 comprises a pair of rail members 25 and 26. The rail member 26 has laterally extending tabs 27 offset at 28 and turned back to form tongues 29 which engage and interlock with the tongues 14 on the 100 stiles 5. In erecting the door, the upper rail is adapted to be installed by interlock-

ing the tongues 29 with the tongues 14 and sliding it down until its upper edge comes substantially flush with the upper edges of the stiles 5, as shown in Fig. 1. The main 5 surface of the rail member 26 may be disposed substantially flush with the adjacent sides of the stiles 5.

The upper rail member 25 may be offset or turned out at 32 to dispose the rail wall 33 10 substantially flush with the opposite sides of the stiles 5. The inner edge of the offset or inturned portion 32 has a marginal flange 35 which is adapted to engage and interlock with a turned back tongue or flange 36 along 15 the adjacent edge of the rail member 26, and the wall member 33 has lateral flanges or tabs 34 turned in to fit or be sprung between the inner edges of the stiles 5. The upper ends of the tongues 12 and 14 and strips 16, 20 terminate short of the top of the door, and extending between the upper rail members 25 and 26 and between the opposite sides of the stiles 5 across the width of the door from one side to the other is a channel member 38. 25 The channel member 38 opens upwardly and the upper edges of its vertical legs may terminate flush with the upper edges of the rail members 25 and 26 and stiles 5. The flanges of the channel member 38 may be spot welded or otherwise suitably secured at 40 to the adjacent rail and stile portions of the door.

The central or intermediate rail 7 comprises a pair of rail members 42 and 43. The rail member 43 is similar to the rail member 35 26, having laterally extending tabs 44 offset at 45 and turned back to form tongues 46 for engagement and interlocking with the tongues 14 of the stile members 5. The main surface of the rail member 43 may be disposed substantially flush with the adjacent 40 sides of the stile members 5 and the rail member 42 may be turned out to dispose its main wall substantially flush with the opposite sides of the stile members.

The rail member 42 is turned in at top and bottom at 48 and 50, respectively, and these turned-in portions 48 and 50 terminate in marginal flanges 52, which marginal flanges 52 are adapted to engage and interlock with 50 turned-back tongues or flanges 53 along the opposite edges of the rail member 43. In erecting the door, the central rail may be assembled by slipping the rail member 42 transversely into proper interlocking engagement with the rail member 43 before slipping the rail member 43 into assembled position between the stiles 5 and into interlocking engagement therewith. The interlocking flanges 52 and tongues 53 bind the intermediate rail members together and against side-wise displacement relative to each other and the engagement with and between the stile members binds them firmly therebetween and against endwise displacement.

Where a sheet metal, such as a steel panel,

is employed, it may comprise a sheet of proper gauge provided along its upper and lower edges with turned back flanges or tongues 56 and 57, respectively. In erecting the door where a panel such as this is employed, the 70 panel may be slipped transversely into interlocking engagement with the rail members, with which the panel interlocks, are slipped between the stile members of the door, so that 75 when the rail members are interlocked with the stile members and slipped into proper position therebetween, the rails, stile members and panels of the door will be firmly secured into a unitary sheet metal door structure. 80

The edges of the panel may be finished by a molding 62, composed of vertical and horizontal metal molding strips fitting within the frame provided by the stile and rail members. The molding strips have inturned marginal 85 flanges 63 terminating in beads 64. For the purpose of securing the molding in place, a plurality of suitable clip members 65 are provided. These clip members have flanges 66, 90 which are adapted to be inter-engaged or interlocked with the tongues 14, 36 and 53, and held in place with the other flanges or tongues interlocking with said flanges or tongues 14, 36 and 53. Outwardly of the flanges 63, the clips 65 are offset at 68 over the outer surface 95 of the panel. The offset portions 68 terminate in tongues extending outwardly and turned back at 70, and the beads 64 of the flanges 63 of the molding strips are adapted to be sprung beneath or behind these turned-back tongues 70 to hold the molding strips securely in place.

The attachment clips 65 for the molding strips, may comprise relatively short lengths placed as desired about the stile and rail members to hold the molding in place, as 105 shown in Fig. 5. The abutting corners of the molding strips are preferably beveled or mitered, and these corners may, upon completion of the door, be welded together. 110

The lower rail member 8 is shown as formed and interconnected similar to the upper rail member 6. It comprises a pair of rail members 76 and 78, the rail member 78 having lateral tongues interlocking with the 115 tongues 14 similar to the tongues 29 of the upper rail member and a turned back flange or tongue 80 along its upper edge for interlocking with a flange 82 along the upper edge of the rail member 76 and with the tongue 83 along the lower edge of the panel 10. Extending the width of the door and secured between the lower edges of the rail members 76 and 78 and the opposite sides of the lower 120 ends of the stile members 5, is a channel member 85. The channel member 85 opens downwardly and its flanges may be spot welded or otherwise suitably secured at 86 to the adjacent rail and side or stile portions of the door.

In the door shown in Figs. 1 to 10, the bot- 130

tom panel 10 may be similarly secured in place and similarly finished with a molding, that is, like the upper panel 9, so that a further detailed description of the same is believed unnecessary. Upon the completion of the door, the opposite ends of the upper intermediate and lower rails 6, 7 and 8, may be welded to the adjacent portions of the stile members 5, and the entire structure thereby joined into a solid, unitary door having great strength.

The lower channel member 85 may be provided with suitable guide pins 88, formed of cast iron, or otherwise, as desired, and suitably secured in the channel 85.

For hanging the door, the upper channel member 38 is provided with suitable hanger blocks 90 secured therein by screws 92, which pass through openings 93 and engage in plates 93' underlying the channel. The openings 93 in the base of the channel 38, through which the bolts 92 extend, are elongated in the direction of the width of the door to permit adjustment of the hanger blocks 90 in that direction. This permits the distance between the hanger blocks 90 to be conveniently adjusted on the job to accommodate the door hanging means in spite of such variations as may occur. Between the screws 92 the blocks 90 have internally threaded openings 92' for hanging the door. The hollow stile members 5 may be provided internally with suitable fillers 94. These fillers 94 may be of cork or other suitable material.

In Fig. 12 the door is shown as provided with a glass or suitable transparent panel 100, which may be substituted for the upper panel of the door of Figs. 1 to 10, or be otherwise placed therein. In this case, the panel 100 is cut or dimensioned to fit between the stile members 5 and the rail members of the door, with their inner surfaces seating upon the inwardly extending flanges 36' of the rail members and the inwardly extending flanges of the stile members. The molding 102 is secured around the opposite side of the edge or margin of the panel 100. The molding 102 may comprise molding strips, as before, which may be secured directly to the adjacent stile members and rail members of the door, as by means of screws 103, as shown in Fig. 12.

In the modification of Fig. 13, the panel 105 is shown as formed of insulating material, such as plaster-board or the like. Such a panel 105 may be substituted for either or both of the panels of the door already described, or it may be otherwise interposed in the door, as desired. It may be mounted and secured in place, as is the panel or pane 100 of Fig. 12, or otherwise as desired.

In the door shown in Fig. 11, the central or intermediate rail of the previous embodiment is omitted and a single panel 106, surrounded by stile members 107 and upper and

lower rail members 108 and 109, is provided. The panel 106 may be of metal, glass or other transparent material or insulating board, as before, and it is shown as finished about its edge or margin with a molding 112.

In Fig. 14 I have shown one manner of attaching an operator or operating member 115 to the stile member 116 of the door. The opposite sides 117 and 118 of the stile member 116 are provided with aligned or registering openings. A metal sleeve 120 fits between the side 118 and the operating member 115, extending through the opening in the wall 117 and properly spacing the wall 118 from the operating member 115. A screw 80 70 75 80 85 90 95 100 105 110 115 120 125 130

A screw 80 extends through the sleeve 120 and has threaded engagement with the operating member 115, the outer end of the screw having a head which cooperates with the wall 118 and the outer end of the sleeve 120 to bind the sides of the stile 116 together and the operating member 115 firmly thereto.

I do not intend to be limited to the precise details and panel arrangements shown or described.

I claim:

1. In a device of the class described, the combination of a stile member having longitudinal tongue means therealong, a rail comprising a first rail member having tongue means adapted to be slipped longitudinally of the stile member into interlocking engagement with the tongue means along said stile member, second tongue means along said rail member, and a second rail member having co-operating tongue means adapted to be slipped transversely of the stile member into interlocking engagement with said second rail tongue means.

2. The herein described stile member for use in door construction comprising a hollow sheet metal stile member having free edges and provided along said edges with turned-back tongues each outside the hollow of the stile member, said tongues lying at substantially right angles to each other with one tongue at right angles to one side of the stile member and the other tongue parallel the opposite side of the stile member, and a common angular sheet metal member extending along and interlocked along its opposite edges with said tongues.

3. In a device of the class described, the combination of a hollow sheet metal stile member having free edges and provided along said edges with turned back tongues, said tongues lying at substantially right angles to each other with one tongue at right angles to one side of the stile member and the other tongue parallel the opposite side of the stile member, an angular sheet metal member extending along and interlocked along its opposite edges with said tongues, and a rail comprising a two piece rail member having one piece interlocked with one of said tongues

and the other piece interlocked directly with said first piece.

4. In a device of the class described, the combination of a frame comprising a hollow sheet metal stile member having free edges and provided along said edges with turned-back tongues, said tongues lying at substantially right angles to each other with one tongue at right angles to one side of the stile member and the other tongue parallel and adjacent the opposite of the stile member, an angular sheet metal member extending along and interlocked along its opposite edges with said tongues, a rail comprising a rail member interlocked with one of said tongues, and a second rail member interlocked with said first rail member, and a panel mounted in said frame and interlocked with said rail.

5. In a device of the class described, the combination of a frame comprising a hollow sheet metal stile member having free edges and provided along said edges with turned-back tongues, said tongues lying at substantially right angles to each other with one tongue at right angles to one side of the stile member and the other tongue parallel and adjacent the opposite side of the stile member, an angular sheet metal member extending along and interlocked along its opposite edges with said tongues, a rail comprising a rail member interlocked with one of said tongues, a second rail member interlocked with said first rail member, a panel mounted in said frame and interlocked with said rail, molding means marginally surrounding said panel, and means interlocked with the frame and with said molding means for securing said molding means in place.

6. In combination, a door having a channel along its upper edge, said channel having an elongated slot, a hanger mounted in said channel, and screw means passing through said slot for adjustably securing said hanger in said channel, the elongation of the slot being across the width of the door and said hanger being adjusted by loosening said screw means and adapted to be clamped in any desired adjusted position by tightening said screw means.

50 7. In combination, a door having opposite stile members, a rail member extending between said stile members, a channel member secured in said rail member and a hanger mounted in said channel member, and means for adjusting the hanger across the width of the door to accommodate same to different positions of the door hanging means across the door opening.

8. In a door of the class described, the combination of a hollow sheet metal stile closed along its outer edge and open along its inner edge, the marginal edge of said stile at one side being turned substantially normal the adjacent side of the stile and having a flange turned back substantially parallel with said

marginal edge, the marginal edge at the opposite side of the stile lying in the plane of the opposite side of the stile and extending inwardly of said first edge, said last marginal edge having a flange turned back substantially parallel to the same and the adjacent side of the stile, a vertical stay member closing the open edge of the stile and having a turned back tongue along one side substantially normal the adjacent side of the stile and interlocking with said first flange and an inward extending tongue along the opposite side and substantially normal to said first tongue and parallel to the opposite side of the stile for interlocking with the flange at the opposite side of said stile member.

9. In a door of the class described, the combination of a hollow sheet metal stile closed along its outer edge and open along its inner edge, the marginal edge of said stile at one side being turned substantially normal the adjacent side of the stile and having a flange turned back substantially parallel with said marginal edge, the marginal edge at the opposite side of the stile lying in the plane of the opposite side of the stile and extending inwardly of said first edge, said last marginal edge having a flange turned back substantially parallel to the same and the adjacent side of the stile, a vertical stay member closing the open edge of the stile and having a turned back tongue along one side substantially normal to the adjacent side of the stile and interlocking with said first flange, an inward extending tongue along the opposite side and substantially normal said first tongue and parallel to the opposite side of the stile for interlocking with the flange at the opposite side of the said stile member, rails comprising two pieces interlocked along longitudinal edges with each other and at opposite ends with the turned back tongues of the stile members which are parallel the adjacent sides of said stile members and a panel laid upon said tongues and interlocking along its longitudinal edges with the longitudinal tongues of the rail members.

10. In a device of the class described, the combination of a pair of hollow sheet metal stile members each having a marginal tongue outside the hollow of the stile members, said tongues lying in substantially a common plane and adjacent and parallel one side of each stile member and a separate two-piece sheet metal rail member extending between said stile members with one rail piece provided at its opposite ends with tongues interlocked directly with the tongues on the stile members outside the hollow of said stile members and the other rail piece interlocked along one edge with said first rail piece, the tongues on the ends of said first rail member lying in substantially a common plane and parallel the side of the rail member.

11. The herein described stile member for

use in door construction, comprising a hollow sheet metal stile member having free edges and provided along said edges with turned-backed marginal tongues outside the hollow 5 of the stile member and at right angles to each other with one tongue at right angles to one side of the stile member and the other

tongue adjacent and substantially parallel to the other side of the stile member and extending inwardly beyond said first tongue. 10

In witness whereof, I hereunto subscribe my name this 28th day of October, 1925.

WAINWRIGHT B. GERVAIS.
